Patented Dec. 5, 1916.

UNITED STATES PATENT OFFICE.

JOHN HAHN, OF LOS ANGELES, CALIFORNIA.

OIL-WELL EQUIPMENT.

1,207,689.

Specification of Letters Patent.

Patented Dec. 5, 1916.

Application filed December 22, 1915. Serial No. 68,173.

To all whom it may concern:

Be it known that I, JOHN HAHN, a citizen of the United States, residing at Los Angeles, in the county of Los Angeles and State of California, have invented a new and useful Oil-Well Equipment, of which the following is a specification.

This invention relates to oil well equipment designed to pump oil from the earth and an object of the invention is to effect 10 the pumping operation by a construction that will produce minimum disturbance of the oil and minimum liability of producing sanding of the well and of the producing strata in the immediate vicinity of the well.

Another object of this invention is to effect the foregoing by a comparatively simple and inexpensive construction.

Another object is to create a reservoir of 20 oil near the bottom of the well so that there will be at all times considerable hydrostatic pressure outward against the oil in the producing strata in order that operation of the pump piston will not produce excessive suction on the producing strata and thereby allow the hydrostatic pressure in the producing strata to force quantities of loosened sand into the well and thereby cause it to be plugged up by the sand.

Other objects and advantages may be disclosed hereinafter.

The accompanying drawings illustrate the invention.

Figure 1 is an elevation mainly in vertical mid section of a well equipment built in accordance with this invention, portions at intervals being broken away to contract the view. Fig. 2 is a reduced elevation partly in section of the gas trap and support shown in Fig. 1 together with a fragment of the well casing. Fig. 3 is an enlarged broken sectional elevation of the gas trap and support together with fragments of the well casing in vertical mid section. Fig. 4 is a plan section on line indicated by x^4-x^4 , Fig. 3, the well casing being omitted. Fig. 5 is a plan section on line indicated by x^5-x^5 , Fig. 3. Fig. 6 is an enlarged sectional elevation of either one of the valve cages and its parts.

There is provided a well casing 1 having oil inlet perforations 2 adapted to let the oil into the casing from the producing strata. The upper end of the casing 1 is provided with a casing head 51 from which

gas can be discharged through a pipe 3 connected to the casing head. Inside of the casing 1 is a tubular discharge conduit in the form of pump tubing 4 which passes through the casing head 51 and is connected 60 by a T 5 to an oil discharge pipe line 6 discharging below the surface of the oil in a closed reservoir or tank 7, portions only of which are shown, said tank being provided with a cover 8 through which a gas 65 outlet tube 9 passes to let gases escape from the tank 7.

The oil discharge pipe 6 is provided between the T 5 and tank 7 with an oil stand pipe or reservoir 10 closed at its upper end 70 by a cap 11 or equivalent.

The pump tubing 4 is provided with a working barrel or pump cylinder 12 in which works a piston 13, said piston and said cylinder being each provided with a 75 valve cage 14. Each valve cage 14 is provided internally with a detachable valve seat 15 held in place by a nut 16, there being inside of each valve cage a valve ball 17 to close onto its seat 15. Each valve cage 14 is 80 provided at its longitudinal axis with a pin 18 fastened into said valve cage and projecting interiorly thereof, the inner projecting end forming a guide stem for a ball-centering block 19 which is provided with 85 a hole 20 to accommodate the pin 18 so that the block 19 can slide up and down on the pin when it is lifted by and falls with the valve ball 17. Each block 19 is provided at 90 its lower ball-engaging end with a concave seat 21 adapted to fit or approximately fit the spherical surface of the ball 17 and is provided in its upper end or liquid pressure-receiving face with an annular recess 22 adapted to be acted on by the oil column 95 above the block passing through openings 23 of the valve cage, said openings extending above the level of the pressure-receiving face 22 at all times, even when the block 19 is in its uppermost position, by reason of the said block having a hub 24 extending above the pressure face 22 and adapted to engage an annular shoulder 25, surrounding the pin 18, when the block 19 is in said uppermost position. The block 19 is preferably made 100 of a non-magnetizable substance such, for instance, as brass.

The foregoing described construction of the valves is of advantage for the reason that there is great tendency for the valve 110

balls to stick to the cage owing to the fact that from some cause not known to me the cages become magnetized and consequently attract the valve balls and hold them in open position so that they do not quickly close when back pressure of the oil comes on them. I obviate the sticking by providing the block 19 and making the same of a non-magnetizable substance. The block 19 also acts as a weight to aid in quick closing of the valve ball 17 from open position.

The lower end of the cylinder 12 is inserted in a pump seat 26 which connects said cylinder to a tubular discharge pipe 27 of a gas trap which is constructed as follows: The discharge member 27 is screw-threaded into a tubular head 28 provided with a downwardly and inwardly directed port or ports 29 which communicate with the interior of a tubular perforated member 30 that is screw-threaded into the lower end of said head 28 and that is intermediate of an outer imperforate tubular member 31 and inner imperforate member 32, said tubular member 30 being provided with inwardly contracted or outwardly expanding perforations 33 arranged in spiral formation circumferentially. The inner tubular member 32 is screw-threaded into a reduced neck 34 of the head 28 and passes downward and extends through a reduced neck 35 of a lower head 36 into which is screw-threaded the lower end of the intermediate tubular member 30. The lower head 36 is provided adjacent the neck 35 with a downwardly and inwardly directed port or ports 37, and the head 28 and head 36 are provided with annular circumferential grooves 38 adjacent annular shoulders 39 of the heads 28, 36 respectively, said annular grooves 38 being provided with packing 40 adapted to pack the joints between the outer member 31 and the heads 28, 36 to prevent leakage, and said heads 28 and 36 being inserted in and tightly fitting the opposite ends of the outer tubular member, and said packing 40 being compressed between the shoulders 39 and the ends of the outer tubular member.

50 Into the lower end of the lower head 36 is screw-threaded a tube 41 surrounding the lower portion of the inner tubular member 32 and communicating through the ports 37 with the interior of the outer tubular member 31 and provided at its lower end with a closure in the form of a cap or plug 42 to form the lower portion of a reservoir of which the upper portion is formed by the intermediate and outer tubular members 30, 31 and head 28. Onto the lower end of the head 36 is screw-threaded a centering support constructed as will now be described. Said support comprises end hubs 43, 44 and resilient spaced apart inwardly bowed spring arms 45 extending

longitudinally from hub to hub, each spring arm being provided at its middle portion with a thickened portion or boss 46 having its outer face 47 curved to fit or substantially fit the inside face of the casing 1, 70 said spring arm being compressed, as in solid lines in Fig. 3, when the faces 47 are in engagement with the inside surface of the casing so that the expansive force of the spring arms is exerted to produce a 75 large amount of friction between the frictional faces 47 and well casing and thus support centrally in the casing whatever elements are connected to the support. Dotted lines α in Fig. 3 indicate positions 80 the spring arms assume when said support is removed from the casing or any tubular member tending to compress said spring arms.

The upper hub 43 is screw-threaded onto 85 the lower end of the lower head 36 and the lower hub 44 is screw-threaded onto a tube 48 surrounding and spaced apart from the tube 41 and having its lower end somewhat above the level of the lower closed end of 90 said tube 41 as in Fig. 1.

From the foregoing it is seen that between the outer tubular member 31 and intermediate tubular member 30 is formed an annular chamber b communicating through the ports 37 with the interior of the tube 41 and that between the intermediate tubular member 30 and inner tubular member 32 there is formed an annular chamber c communicating through the perforations 33 with the chamber b and communicating through the ports 29 with the outside of the gas trap. The perforations 33 are in the lower half of the tubular member 30, see Fig. 2. The upper valve cage 14 is connected by a sucker line 105 49 to operating means as a walking beam 50 or equivalent.

In practice a well will be equipped with the device as shown and the oil will enter the casing through the perforations 2 and oil will flow from the interior of the casing through the ports 29 into the chamber c and through perforations 33 into the chamber b , thence through ports 37 into the space d between the tube 41 and inner tubular member 32, and thence into the lower open end of the inner member 32 and said oil will rise in said inner tubular member through the tube 27 into the pump cylinder 12 to the same level as the oil in the casing. The piston will be operated through its sucker line 49 and the walking beam 50 so as to lift the oil in the pump tubing and force said oil through the pipe line 6 into the tank 7. The flow of oil is stabilized by reason of the stand pipe 10 and also by reason of the chambers b , c .

It is noted that the ports 29, 37 are directed in such manner as to tend to bleed the bubbles of gas that may be in the oil out- 130

ward in a direction opposite to the flow of the oil through the gas trap and it is also noted that the perforations 33 are reduced inwardly so as to allow the bubbles of gas 5 rising in the chamber *b* to flow without hindrance therethrough into the chamber *c* from whence said bubbles can escape through ports 29, said escape being facilitated by reason of said ports 29 slanting upward and 10 outward.

The foregoing construction is of advantage in minimizing the amount of gas that can pass from the interior of the casing to the pump cylinder and its piston thus preventing to a great extent compression of a 15 body of gas within the cylinder and piston tending to prevent effective pumping action of the piston on the oil as is readily understood. The valve balls 17 will act quickly 20 because of provision of the non-magnetizable blocks 19. It is also seen that liability of the piston to produce an undesirable excessive suction on the oil bearing strata is minimized, thereby minimizing liability of plugging 25 the well and producing strata adjacent the well with sand which otherwise would tend to be drawn in by the suction.

The tube 48 acts as a weight to tend to elongate the centering support and thereby 30 force the bosses 46 tightly against the well casing, thus aiding the expansive force of the arms 45 to create friction between the bosses and casing so as to clutch the support to the inside of the casing.

35 As seen in Fig. 2 by far the greater portion of the intermediate tubular member 30, in this instance about two thirds, is above the perforations 33, and this provision is so as to insure that at each stroke of the piston 40 the oil in the chamber *b* will continue to cover the perforations so that gas will not enter the chamber *b* through said perforations from the chamber *c*, thus practically excluding gas from the pump barrel. The 45 provision of the reservoir or chamber *b* also insures uniform flow of the oil to the pump barrel and avoidance of its flow in surges, such surges being detrimental as they produce agitation and consequent emulsification 50 of the oil when water is present and also lower the pressure at intervals so as to free the lighter gaseous hydrocarbons dissolved in the oil and of great value.

The foregoing will enable those skilled in 55 the art to which the invention appertains to make and use said invention.

I claim:

1. In combination, inner, outer and intermediate tubular members spaced apart from 60 one another to form annular chambers, the intermediate tubular member having perforations, a head closing the upper ends of said chambers and provided with a port communicating with the interior of the inner chamber, a head closing the lower ends 65 of the chambers and provided with a port

of the chambers and provided with a port communicating with the outer chamber, a tube extending down from the lower head and closed at its lower end and having its upper end communicating with the port in 70 the lower head, said inner tubular member extending through the lower head, pump tubing connected to the upper head and provided with a cylinder, a piston in the cylinder, and means to operate said piston. 75

2. In combination, pump tubing having a cylinder, a piston in said cylinder, means to operate said piston, well casing, a centering support connected to said tubing, said support comprising tubular end hubs and resilient inwardly bowed spring arms extending from hub to hub and said spring arms being provided with outwardly projecting bosses to frictionally engage the inside surface of the well casing, and means tending 80 to straighten said spring arms so as to hold the bosses tightly against the casing. 85

3. In combination, pump tubing, means forming a reservoir, means connecting the reservoir to the lower end of the pump tubing, said reservoir having a liquid-sealed inlet port and extending a substantial distance above said port, an oil discharge pipe connected to the upper end of the pump tubing, and a stand pipe connected to said oil 90 discharge pipe to minimize fluctuation of pressure in the reservoir. 95

4. In combination, pump tubing, inner, outer and intermediate tubular members spaced apart from one another to form annular chambers, the intermediate tubular member having perforations, a head closing the upper ends of said chambers and provided with a port communicating with the interior of the inner chamber and connected to the pump tubing, a head closing the lower ends of the chambers and provided with a port communicating with the outer chamber, and a tube extending down from the lower head and closed at its lower end and having its upper end communicating with the port in the lower head, said inner tubular member extending through the lower head. 100 105 110

5. In combination, inner, outer and intermediate members spaced apart from one another to form annular chambers, the intermediate tubular member having outwardly expanding perforations, a head closing the upper ends of said chambers and provided with a port communicating with the interior of the inner chamber, a head closing the lower ends of the chambers and provided with a port communicating with the outer chamber, a tube extending down from the lower head and closed at its lower end and having its upper end communicating with the port in the lower head, said inner tubular member extending through the lower head, pump tubing connected to the upper head and provided with a cylinder, a piston 115 120 125 130

in the cylinder, and means to operate said piston.

6. In combination, inner, outer and intermediate tubular members spaced apart from one another to form annular chambers, the intermediate tubular member having perforations, a head closing the upper ends of said chambers and provided with a port communicating with the interior of the inner chamber, a head closing the lower ends of the chambers and provided with a port communicating with the outer chamber, a tube extending down from the lower head and closed at its lower end and having its upper end communicating with the port in the lower head, said inner tubular member extending through the lower head, pump tubing connected to the upper head and provided with a cylinder, a piston in the cylinder, and means to operate said piston.

7. In combination, inner, outer and intermediate tubular members spaced apart from one another to form annular chambers, the intermediate tubular member having perforations, a head closing the upper ends of said chambers and provided with an upwardly and outwardly slanting port communicating with the interior of the inner chamber, a head closing the lower ends of the chambers and provided with an upwardly and outwardly slanting port communicating with the outer chamber, a tube extending down from the lower head and closed at its lower end and having its upper end communicating with the port in the lower head, said inner tubular member extending through the lower head, pump tubing connected to the upper head and provided with a cylinder, a piston in the cylinder, and means to operate said piston.

8. In combination, casing, pump tubing in the casing, a gas trap connected to the pump tubing, a centering support on the gas trap, and means operating by its weight to hold the centering support friction tight in the casing.

9. In combination, casing, pump tubing in the casing, a gas trap connected to the pump tubing, and a friction supported centering device in fixed relation with the gas trap to support the gas trap in the casing.

10. In combination, pump tubing, means forming a reservoir, said reservoir having an inlet port near its upper end only and the upper portion of said reservoir being formed by intermediate and outer tubular members, a tubular member communicating at its lower end with said reservoir, and means connecting the tubular member and reservoir to the pump tubing.

11. In combination, an upper head, a lower head having a neck, an inner tubular member fastened to the upper head and passing through said neck of the lower head, other tubular members concentric with the inner

tubular member and spaced from one another to form a chamber, one of said other tubular members having screw-threaded connection with the upper and lower heads, and the other one of said other tubular members loosely engaging each of said heads, the upper head having a port communicating with the interior of the intermediate tubular member, and the lower head having a port opening from said chamber to the inside of the head below said neck, and the intermediate tubular member having perforations, a cylinder connected to the upper head, a piston in said cylinder, and means to operate said piston.

12. In combination, tubular heads having annular grooves and having ports opening therethrough, packing in the annular grooves, concentric tubular members extending from head to head, the inner tubular member opening through both heads and one of the other tubular members having screw-threaded engagement with each of said heads and the third one of said tubular members engaging the packing in the grooves and the intermediate member having perforations, a cylinder connected to one of said heads, a piston in the cylinder, and means to operate said piston.

13. In combination, tubular heads having annular shoulders and annular grooves adjacent said shoulders and having ports opening therethrough, packing in the annular grooves and projecting therefrom concentric, tubular members extending from head to head, said heads closing the ends of two of the tubular members, and the inner tubular member opening through both heads and one of the other two tubular members having screw-threaded engagement with each of said heads and the other of the two tubular members having its ends compressing the projecting parts of the packing against said shoulders, a cylinder connected to one of said heads, a piston in the cylinder, and means to operate said piston.

14. In combination, a gas trap having a tubular perforated member and having a tubular imperforate member surrounding and spaced apart from the perforated member and extending for a substantial distance above the level of the perforations in the tubular member, tubular heads at the ends of the tubular members, one of said heads having a port opening from its exterior and communicating with the interior of the perforated member and the other head having a port communicating with the space between the tubular members and with the interior of said other head, a cylinder connected to one of said heads, a piston in said cylinder, and means to operate said piston.

15. In combination, pump tubing, means forming a reservoir, and means connecting the reservoir to the lower end of the

pump tubing, said reservoir having a liquid-sealed inlet port and extending a substantial distance above said port.

16. In combination, a tubular member, a support having bowed arms provided with bosses engaging said tubular member, and a weight connected to said support tending to straighten said arms to prevent relative end-wise movement between said support and tubular member.

17. In combination, inner, outer and intermediate tubular members spaced apart from one another to form annular chambers, the intermediate tubular member having perforations, a head closing the upper ends of said chambers and provided with a port com-

municating with the interior of the inner chamber, a head closing the lower ends of the chambers and provided with a port communicating with the outer chamber, a tube 20 extending down from the lower head and closed at its lower end and having its upper end communicating with the port in the lower head, said inner tubular member extending through the lower head, and pump 26 tubing connected to the upper head.

Signed at Los Angeles, California, this 17th day of December, 1915.
